BATTERY LIFTER

Felix E. Brown, Bethlehem, Pa.

Application June 11, 1946, Serial No. 675,856

1 Claim. (Cl. 294—103)

This invention relates to a battery lifter and has for its primary object to facilitate the lifting and carrying of storage batteries or accumulators of types commonly employed in the electrical systems of motor vehicles.

Another object is automatically to clamp the terminal posts of a storage battery or accumulator, and sustain the battery suspended by the clamps and posts, and to facilitate the rapid and convenient disengagement of the clamps from the terminal posts when so desired.

Among its features my invention embodies a pair of battery post engaging clamps, each of which comprises a substantially L-shaped clamp jaw one leg of which is of a width greater than the opposite leg, the wider leg of each clamp jaw having a shallow substantially V-shaped notch in its free end for receiving a battery post, a battery post embracing clamp ring loosely fitted on the narrower leg of the clamp jaw to slide longitudinally thereof and swing in a limited arc thereabout, and a strap of flexible non-conductive material of a width substantially equal to the wider leg of the clamp jaw secured to the narrower leg of the clamp jaw in spaced relation to the wider leg thereof to cooperate with the wider jaw in restricting movement of the clamp ring longitudinally of the narrower jaw.

In the drawings,

Figure 1 is a fragmentary perspective view of a battery and terminal post thereof, showing this improved battery lifter in place thereon,

Figure 2 is a vertical sectional view through a battery post and clamp jaw showing the clamp in battery sustaining position,

Figure 3 is a view similar to Figure 2, showing the manner in which the clamp may be loosened,

Figure 4 is a perspective view of the L-shaped clamp jaw, and

Figure 5 is a perspective view of the clamp ring showing the L-shaped clamp jaw in place therein in broken lines.

Referring to the drawings in detail a battery 10 is shown as equipped with a terminal post 11 and it is to be understood that a like post is carried by the battery adjacent its opposite end but in the present illustration only one end of the battery is disclosed.

My improved battery lifter designated generally 12 comprises a pair of clamps designated generally 13 each of which comprises an L-shaped clamp jaw 14, one leg 15 of which is wider than the opposite leg 16 and formed with a shallow V-shaped notch 17 in its free end to provide two point contact with the terminal part of a battery.

5 The clamp jaw 14 is stamped from a sheet metal blank, and the narrower leg 16 thereof is curved as at 18 at its free end to avoid chafing of the lifting strap, to be more fully hereinafter described. Formed in the narrower leg 16 of the jaw 14 are longitudinally spaced rivet receiving openings 19 through which rivets 20 are adapted to extend. Formed at the junction of the narrower and wider legs of the jaw 14 intermediate the side edges thereof is an upstruck reinforcing rib 21 which serves rigidly to hold the legs 15 and 16 in proper angular relation and aid them to resist bending under the weight of the battery.

10 Mounted to slide longitudinally on the narrower leg 16 of the clamp jaw 14 is a clamp ring 15 designated generally 22 which comprises an elongated body 23 having at one end a rounded portion 24. This body is also formed with an elongated opening 25 which extends longitudinally thereof and terminates in a rounded portion provided with inwardly projecting teeth 26 at one end of the body 23 for penetration of any incrustation which may accumulate on a battery part. The opposite end of the elongated opening 25 is formed with laterally extending notches 27 forming shoulders 28, the purpose of which will 15 more fully hereinafter be explained.

15 In assembling the device a clamp 13 is riveted by means of the rivets 20 to opposite ends of a strap 29 of flexible non-conducting material having a width substantially equal to the width of the wider jaw 15. It will thus be seen that the strap 29 may be used as the lifting handle 12 so that the device may be handled as a unit. The clamp ring 22 will then be confined between the end of the strap 29 and the leg 15 of a clamp jaw 14 so as to have limited pivotal movement on the narrower leg 16 of the clamp member 14, with the shoulders 28 engaging the front or exposed face 20 of the narrower leg 16 so as to hold it in proper projected relation to the notch 17 in the leg 15. The dimensions of the notch 17 are such as to permit a limited pivotal movement of the ring 22 about the narrower leg 16 so that when the clamp 25 13 is in position to embrace a battery post 11 the clamp ring 22 will fall by gravity into the position illustrated in Figures 1 and 2 so as to cooperate with the walls of the V-shaped notch 17 in gripping the post 11. The end of the clamp ring 22 which projects beyond the end of the leg 15 is preferably bent downwardly as illustrated in order that when a lift is exerted on the strap 29 the teeth 26 will bite into the post 11 and thus cooperate with the walls of the notch 17 to firmly clamp the device about the post. Consequently,

the greater the strain on the strap or handle 12, the tighter will be the grip of the clamp 13 about its respective battery post. As soon as the battery has found its resting place, downward pressure on the strap 29 will throw the parts into the position illustrated in Figure 3, thus rocking the clamp jaw 14 about its pivotal connection with the clamp ring 22 so that the walls of the notch 17 will disengage the post and the device may be then lifted off of the battery without requiring the use of a hand other than that manipulating the strap 29.

It is to be understood that the distance from the apex of the V-shaped notch 17 to the junction of the legs 15 and 16 is so determined as to produce maximum strength of the unit and govern the angle of the entire unit so as to permit the use of a minimum material for the lifting strap.

While in the foregoing there has been shown and described the preferred embodiment of this invention it is to be understood that minor changes in the details of construction, combination and arrangement of parts may be resorted to without departing from the spirit and scope of the invention as claimed.

I claim as my invention:

A battery lifter comprising a pair of battery post engaging clamps each of which comprises a substantially L-shaped clamp jaw one leg of which is of a width greater than the opposite leg, the wider leg of each clamp jaw having a shallow substantially V-shaped notch in its free end for receiving a battery post, an elongated bat-

tery post embracing clamp ring the opening through which is of lesser size than the width of the narrower leg of its respective clamp jaw, said ring having opposed notches adjacent one end for the reception of opposite side edges of the narrower leg of its respective clamp jaw slidably to support the clamp ring for limited pivotal movement on the said narrower leg of the clamp jaw and in a position for cooperation with the walls of the V-shaped battery post receiving notch in gripping a battery post, said ring having internal teeth therein at its other end, said other end being bent downwardly so that the teeth will incline upwardly and inwardly of said ring and bite upwardly into the battery post, a strap of flexible non-conducting material fixed to the narrower leg of the clamp jaw in spaced relation to the wider leg thereof to serve as a lifting handle and limit the distance the clamp ring may move away from the wider leg of the clamp jaw and the end of the narrower leg of the L-shaped clamp jaw remote from the wider leg thereof curving away from the strap as its end is approached.
